UNITED STATES PATENT OFFICE.

SYLVESTER S. GIERHART, OF WANETTE, OKLAHOMA.

WRAPPER-CUTTER.

1,134,043.

Specification of Letters Patent. Patented Mar. 30, 1915.

Application filed June 12, 1914. Serial No. 844,734.

To all whom it may concern:

Be it known that I, SYLVESTER S. GIERHART, a citizen of the United States, residing at Wanette, in the county of Pottawatomie, State of Oklahoma, have invented certain new and useful Improvements in Wrapper-Cutters; and I do hereby declare the following to be a full, clear, and exact description of the invention, such as will 10 enable others skilled in the art to which it appertains to make and use the same.

This invention relates to a cutting device, and more particularly to a cutting device to be used to cut paper wrappers from bundles.

15 In wrapping packages it has become the common practice to draw the wrapper tight about the material within the packages and to paste the said edges of the wrapper together. When packages are wrapped in 20 this manner it is sometimes very difficult to strip the wrapper therefrom and it becomes tiresome to use the finger in tearing the wrapper.

An object of the invention is to provide a 25 simple and efficient device which may be placed on the finger and by means of which wrappers may be readily cut so as to be removed from the package.

A further object of the invention is to so 30 construct a device that it will brace the first joint of the finger on which it is mounted.

With these and other objects in view, such 35 as will appear as the description progresses, my invention comprises the combination and arrangement of parts as herein set forth and subsequently claimed.

40 Referring to the drawing: Figure 1 is a perspective view of the device showing the operation thereof. Fig. 2 is a side elevation with a portion broken away.

45 Referring to the drawing by reference characters wherein like parts are indicated by like characters throughout the several views, my device comprises a tubular body portion 1 having a longitudinally extending hole 2 therein, which hole is tapered toward the cutting edge of the device. In this tubular member 1 is formed a slot 3 which opens on the rear edge of the said member 50 so that the body member will accommodate itself to fingers of various sizes, it being of course understood that the device is made of light spring metal and may be either stamped or bent into form. The forward

end of this body portion 1 is cut away so 55 as to form a finger 4, said finger being pointed, as at 5, at its forward end, and the edges of said finger being sharpened. The portion of the body 1 immediately beneath the finger 4, which in fact forms the bottom of 60 said finger is flattened so that in cutting a wrapper from a package of paper the device will lie flat upon the paper in the package.

Formed integrally with the finger 4 is a 65 centrally located cutting blade 5' having a sharpened forward edge 6. The edge of this cutting blade joins the finger 4 a short distance rearwardly of the forward end thereof and it then extends upwardly and 70 rearwardly as may be seen from the drawing. This cutting blade extends upwardly beyond the upper edge of the body portion 1 so as to form a projection 7.

In use the device is placed upon the finger 75 of the operator, preferably the second finger, and is held thereon by the clamping action of the body portion 1. The hole 2 in this body portion is of sufficient length to allow the finger to be inserted beyond the first 80 joint so that the body portion will brace the said joint. In opening a package of paper for instance where the wrapper has been securely pasted in place thereon, the ends of the said wrapper are broken and the finger 85 4 is then inserted beneath the edge of the wrapper and the device pushed across the same, thus causing the cutting edge of the blade 5' to cut the said paper and the wrapper may then be readily removed. 90

It has been found that as the device is of very small construction it may be placed upon the finger and it will not interfere with the operator's work other than cutting the wrappers. 95

In using this device should the package be tied with cord it is not necessary to even remove the cord for as the device moves across the wrapper and the cord engages the cutting edge 6 of the blade 5' the cord 100 will be severed.

From the foregoing description it may be seen that I have provided a very simple and efficient device, and one by means of which the paper wrappers of packages may 105 be readily removed from the said packages.

I do not wish to be limited to the particular construction shown, for it is obvious that

numerous changes may be made within the scope of the invention as defined by the claims.

What is claimed is:—

- 5 1. In a device of the class described, a tubular body portion having a longitudinally extending hole therein, the said body portion being adapted to be mounted on the finger of an operator and the length of the hole being sufficient to allow the operator to insert his finger therein beyond the first joint, a flat finger formed integrally and extending forwardly from the body portion, a vertically disposed blade formed integrally 10 with the body portion and the said finger, the forward edge of said blade being joined to the finger a short distance rearwardly of

the forward end thereof, and inclined upwardly and rearwardly.

2. A device of the class described, a flat finger having knife edges, a vertical cutting blade formed integrally therewith, a cutting edge on said blade being joined to the finger rearwardly of its forward end and extending upwardly and rearwardly therefrom, and means for attaching the device to the finger of an operator. 20 25

In testimony whereof, I affix my signature, in the presence of two witnesses.

SYLVESTER S. GIERHART.
